UNITED STATES PATENT OFFICE.

ARTHUR JOSEPH TOOL, OF MURDOCK, NEBRASKA.

AIR-PUMP FOR OIL-CANS AND OTHER CONTAINERS.

1,197,410.

Specification of Letters Patent.

Patented Sept. 5, 1916.

Application filed November 28, 1914. Serial No. 874,412.

To all whom it may concern:

Be it known that I, ARTHUR J. TOOL, a citizen of the United States, and a resident of Murdock, in the county of Cass and State of Nebraska, have invented a new and Improved Air-Pump for Oil-Cans and other Containers, of which the following is a full, clear, and exact description.

My invention, while applicable to containers generally from which a fluid is to be dispensed, is more particularly intended for embodiment in oil cans.

The invention relates especially to that type of can equipped with an air pump whereby to produce air pressure within the can for discharging the contents thereof under pressure.

Objects of my invention are to provide an efficient pump in compact form and conveniently disposed on the can body; to provide a pump for the indicated purposes, of the diaphragm type, in which the diaphragm may be flexed by a finger of the hand holding the can and the said finger at the same time control the air inlet of the pump; to provide a pump of the indicated character in which a vent may be controlled also by the hand operating the pump whereby to arrest the discharge of the fluid by relieving the pressure in the can.

The invention will be particularly explained in the specific description following.

Reference is had to the accompanying drawings forming part of this specification, in which similar characters of reference indicate corresponding parts in all the views, and in which:

Figure 1 is a vertical section of a can equipped with my invention; Fig. 2 is a plan view of the air pump; Fig. 3 is a detail cross-section on the line 3—3 of Fig. 1; Fig. 4 is a side elevation of the parts in section showing another form of the invention; and Fig. 5 is a side elevation of still another form of pump, the can being in vertical section.

Referring particularly to the form shown in Figs. 1 to 3, the body 10 of the can may have any approved shape, that indicated being the conventional form of an oil can. The can is provided with a discharge nozzle 11, and extending into the can from the inner end of the nozzle is an air pipe 12, the lower end of which is adjacent to the bottom of the can. The top of the can may be equipped with any approved filling cap 13.

My improved air pump designated generally by the numeral 14 is supported on the top of the can by an air tube 15 extending from the base of the pump to the can top 60 and communicating with the interior of the can. The base of the pump has a discharge orifice 16 commanded by a check valve 17, the stem 18 of which has guided movement in a spider 19 disposed in the air tube 15. 65

A dome shaped flexible diaphragm 20 forms the front of the pump and is provided with an air inlet. At the center of the diaphragm are an outer disk or washer 21 and an inner disk or washer 22, which are 70 clamped to the diaphragm by a tubular washer 23 constituting the air inlet. Within the pump beneath the diaphragm 20, and centrally disposed, is a compression spring 24, the inner end of which rests on the base 75 of the pump, the spring tending to normally maintain the diaphragm in the outer position, but yielding to the depression of the diaphragm in the operation of the pump. Thus the spring supports the diaphragm and 80 is located directly adjacent to the air inlet 23, so that in the operation of the pump by a flexure of the diaphragm 20, the finger that depresses the diaphragm may also conveniently open and close the air inlet 23. 85

In order to clamp the diaphragm 20 air tight, the body of the base of the pump is formed with a peripheral annular flange 14^a formed with a coarse screw thread, and from the top of the annular flange there extends 90 radially inward a flange 14^b provided with an annular depression 14^c. The diaphragm 20 is formed with an edge flange 20^a which seats on the flange 14^b over the depression 14^c. The connection of the parts is completed 95 by a clamp ring 25 threaded to take onto the threaded peripheral flange 14^a at the base and having an outer flange 25^a extending radially inward over the flange 20^a of the diaphragm. The flange 25^a is formed with 100 a depressed bead 25^b alining with the depression 14^c of the base flange whereby to crimp the flange 20^a of the diaphragm and bind it tightly between the flanges 14^b, 25^a.

The body 10 is equipped with handle elements of a character to permit of the can being grasped bodily and yet leaving the fingers of the hand free to manipulate the pump and also to control a vent 15^b which is formed in a lateral bulge or enlargement 15^a 110 on the air tube 15 adjacent to the pump 14. Thus there is a handle 26 in the form of a

vertical, oblong, looped wire attached to the body of the can at the exterior beneath the pump and a ring handle 27 disposed above the handle 26, said ring handle being secured 5 to the top of the can and in contact with the underside of the pump base. A brace 28 may be secured to the nozzle 11 and to the air tube 15.

In Fig. 4 the container 10, the pump with 10 its various elements, as well as the handles 26, 27 are the same as in Fig. 1. The air tube 15^e that sustains the pump 14 is formed with a lateral vent opening 15^d which is commanded by a valve 30. The said valve is 15 disposed on the outside of the tube 15^e and is pivoted as at 31 between lugs 31^a on said tube. The valve is provided with an operating arm 32 which extends adjacent to the nozzle 11, and there is a compression spring 20 33 interposed between the nozzle and the said operating arm. The spring 33 normally maintains the valve closed. Pressure 25 by finger of the hand holding the can will serve to raise the valve 30 and permit the air to escape to arrest the discharge of the fluid from the nozzle.

In the form shown in Fig. 5 the pump as 30 well as the nozzle 11^a and the inner discharge tube 12^a are carried by the filling cap 13^a so that all are removable with the said cap. In this way the cap may be applicable to cans already made. The pump 14 is the same as in Figs. 1 and 4. The air tube 15^e, 35 however, extends in a direction toward the nozzle, and has a downward extension 15^g extending through the cap 13^a adjacent to the nozzle. A lateral vent opening 15^h is formed in a lateral bulge 15^f of the air tube. To brace the pump and provide gripping 40 elements for the finger, a ring 27^a is disposed between the base of the pump and the cap 13^a and secured to both as well as to the air

tube 15^e. The ring 27^a is disposed beneath the air tube 15^e. A similar ring 34 is positioned above the air tube 15^e and suitably 45 secured to the latter as by soldering, as well as to the inner side of the pump 14 and to the nozzle 11^a.

Having thus described my invention, what I claim as new and desire to secure by Letters Patent, is:

1. An air pump for application to a container to direct air thereto, said pump including an air pipe adapted to be secured at one end to a container, said air pipe having a lateral vent opening, a diaphragm pump having a base secured to and rigid with the said pipe, above and adjacent to the air vent, and a handle beneath said rigid base at the opposite side of the pipe from the vent to permit the pump to be grasped and operated and the said vent to be controlled by a finger of the hand operating the pump. 55

2. An air pump for application to a container to direct air thereto, said pump including an air pipe adapted to be secured at one end to a container, said air pipe having a lateral vent opening, a manually operated valve commanding the said opening, a diaphragm pump having a base secured to and rigid with the said pipe, above and adjacent to the air vent, and a handle beneath said rigid base at the opposite side of the pipe from the vent to permit the pump to be 60 grasped and operated and the said vent to be 75 controlled by a finger of the hand operating the pump. 70

In testimony whereof I have signed my name to this specification in the presence of two subscribing witnesses.

ARTHUR JOSEPH TOOL.
